United States Patent Office

Des. 195,183
Patented May 7, 1963

195,183

BOAT

James O. Thomas, 3253 McGill Road, Cincinnati, Ohio

Filed Sept. 22, 1960, Ser. No. 62,233

Term of patent 14 years

(Cl. D71—1)

Fig 1

Fig 2

FIG. 3

FIG. 4

FIG. 5

FIG. 6

FIG. 1 is a front perspective view of a boat showing my new design.

FIG. 2 is a rear perspective view thereof.

FIG. 3 is a side elevational view thereof.

FIG. 4 is a top plan view thereof.

FIG. 5 is a bottom plan view thereof.

FIG. 6 is a rear elevational view thereof.

The dominant features of my design reside in the portions shown in full lines.

I claim:

The ornamental design for a boat, substantially as shown and described.
